(57) **CLAIM**

The ornamental design for bag for distribution of particulate materials having handle, as shown and described.

DESCRIPTION

FIG. 1 is a top plan view of a first embodiment of a bag for distribution of particulate materials having handle; the bottom plan view being a mirror image thereof; the left, right, front, and back views being plain and unornamented;

FIG. 2 is a top plan view of a second embodiment of my new design, the bottom plan view being a mirror image thereof; FIG. 3 is a left elevational view of the design depicted in FIG. 2, the right elevational view being a mirror image thereof;

FIG. 4 is a rear elevational view of the design depicted in FIG. 2;

FIG. 5 is a front elevational view of the design depicted in FIG. 2;

FIG. 6 is a top plan view of a third embodiment of my new design, the bottom plan view being a mirror image thereof; FIG. 7 is a left elevational view of the design depicted in FIG. 6, the right elevational view being a mirror image thereof; and,

FIG. 8 is a front elevational view of the design depicted in FIG. 6, the rear elevational view having an identical appearance as that shown in FIG. 4.

The sole differences between embodiments 1 and 2 are the bag is filled with material in embodiment 2, and the side seal being in place in embodiment 2. The sole difference between embodiments 2 and 3 is the end seal has been removed in embodiment 3 to expose a perforated gusset.
